Inventor
Ira J. Young.
By Hiram Young, Atty.

UNITED STATES PATENT OFFICE.

IRA J. YOUNG, OF ST. LOUIS, MISSOURI, ASSIGNOR TO GREAT WESTERN WIRE FENCE & MFG. CO., OF ST. LOUIS, MISSOURI, A CORPORATION OF MISSOURI.

WIRE MAT.

970,595.

Specification of Letters Patent. Patented Sept. 20, 1910.

Application filed November 27, 1908. Serial No. 464,983.

To all whom it may concern:

Be it known that I, IRA J. YOUNG, a citizen of the United States, and resident of St. Louis, Missouri, have invented certain new and useful Improvements in Wire Mats, of which the following is a specification containing a full, clear, and exact description, reference being had to the accompanying drawings, forming a part hereof.

10 My invention relates to a wire fabric particularly intended for use as a mat, the object of my invention being to construct a simple, inexpensive and substantial fabric, the main body portion of which is held in a 15 substantial manner above the floor or pavement on which the mat is placed.

To the above purposes, my invention consists in certain novel features of construction and arrangement of parts which will be 20 hereinafter more fully set forth, pointed out in the claims, and illustrated in the accompanying drawings, in which:

Figure 1 is a plan view of a mat constructed in accordance with my invention; 25 Fig. 2 is a section taken on the line 2—2 of Fig. 1; and Fig. 3 is a plan view of one of the longitudinally extending wires of the mat.

Referring by numerals to the accompanying drawings: 1 designates the longitudinally extending wires forming the body of the mat, in which are formed, at equal distances apart, the vertically disposed circular loops 2, the same projecting downward 35 below the plane occupied by the sections of wire between said loops, and these last mentioned sections are bent at angles relative to the plane occupied by the loops 2, and thus each longitudinal wire has a zigzag shape 40 with the loops 2 at the points between the bent portions.

A number of the wires 1 are arranged side by side, with the loops 2 of an adjacent pair of wires. Coinciding and passing 45 through each row of loops 2 are straight transverse wires 3, the ends of which extend through and are tied to vertically disposed loops 4, which are formed at equal distances apart in a pair of side wires 5 which form 50 the edges of the mat, and which loops 4 coincide with the transverse rows of loops 2. The loops 2 are of such size as that the wires 3 fit snugly therein, and as said loops occupy

vertical positions and project downward from the bodies of the wires 1 and 5, said 55 last mentioned wires are held in a firm and substantial manner in a plane above the floor or pavement on which the mat is located.

A mat of my improved construction is 60 simple, light, strong and durable, and can be very easily and cheaply manufactured.

I claim:

1. A mat constructed of a series of longitudinally extending wires, each wire being 65 bent so that its ends occupy a substantially horizontal plane and the body portion between the ends occupies a position at an angle relative the ends, a vertically disposed loop at each end of each wire and transversely disposed wires extending through 70 the loops.

2. A mat constructed of a series of longitudinally extending wires, each wire being bent so that when assembled the wires are of 75 zigzag form, a vertically disposed loop at each end of each wire, transversely disposed wires extending through the loops and binding wires located at the sides of the mat to which binding wires the ends of the transverse 80 wires are united.

3. A mat constructed of a series of longitudinally extending wires, each wire being bent so that when assembled the wires are of zigzag form, a vertically disposed loop at 85 each end of each wire, projecting below the plane occupied by the bodies of the wires and transversely disposed wires extending through the loops.

4. A mat constructed of a series of longitudinally extending wires, each end of each wire being bent into a vertically disposed loop, projecting below the plane occupied by the bodies of the wires, transverse wires extending through the loops and binding wires 95 located at the sides of the mat to which binding wires the ends of the transverse wires are united.

In testimony whereof, I have signed my name to this specification, in presence of two 100 subscribing witnesses.

IRA J. YOUNG.

Witnesses:

M. P. SMITH,
E. L. WALLACE.
